UNITED STATES PATENT OFFICE.

NICHOLS S. SCOTT, OF FORT BENNING, GEORGIA.

SPEAR.

Application filed August 23, 1922. Serial No. 584,866.

To all whom it may concern:

Be it known that NICHOLS S. SCOTT, a citizen of the United States, residing at Fort Benning, in the county of Chattahoochee and State of Georgia, has invented certain new and useful Improvements in Spears, of which the following is a specification, reference being had to the accompanying drawings:

10 This invention relates to certain improvements in spears and has relation more particularly to a device of this general character especially designed and adapted for use in picking up paper, trash or the like and it is an object of the invention to provide a novel and improved device of this general character comprising a penetrating member together with means for freeing the penetrating member of the trash or the like 20 collected thereon.

The invention consists in the details of construction and in the combination and arrangement of the several parts of my improved spear whereby certain important 25 advantages are attained and the device rendered simpler, less expensive and otherwise more convenient and advantageous for use, as will be hereinafter more fully set forth.

The novel features of my invention will 30 hereinafter be definitely claimed.

In order that my invention may be the better understood, I will now proceed to describe the same with reference to the accompanying drawings, wherein:

35 Figure 1 is an elevational view of a spear constructed in accordance with an embodiment of my invention;

Figure 2 is an enlarged fragmentary view partly in section and partly in elevation illustrating in detail certain features of the device as herein disclosed; and

Figure 3 is a sectional view taken substantially on the line 3—3 of Figure 1.

As herein disclosed, my improved spear 45 comprises an elongated handle member 1 provided at one end portion with a hand grasp 2. The opposite end portion of the handle member 1 has extending outwardly from the axial center thereof an elongated penetrating member 4, the outer or free extremity α of which being pointed so that the same may be readily and conveniently forced through paper, trash or the like to be collected.

55 5 denotes a cross member provided at its central portion with an opening 6

through which the penetrating member 4 is freely disposed, the movement of the member 5 inwardly of the penetrating member 4 being limited by contact with said member 5 with the adjacent end of the handle member 1.

7 denotes a second cross member provided in its central portion with an opening 8 through which the handle member 1 is freely disposed. The extremities of the cross member 7 are connected with the extremities of the cross member 5 by the side members or braces 9 whereby the cross members 5 and 7 are caused to have unitary movement in the same direction longitudinally of the handle member 1 and the penetrating member 4.

The extremities of the cross member 7 also have secured thereto the retractile members or springs 10 which converge toward the handle member 1 and are anchored thereto as at 11. These retractile members or springs 10 serve to normally maintain the cross members 5 and 7 at the limit of their movements inwardly of the handle member 1 and the penetrating member 2.

In practice the user manipulates the device by taking hold of the hand grasp 2 and forcing the penetrating member 4 through paper, trash or the like to be collected and when it is desired to free the penetrating member 4, of such matter collected thereon, the member 5 may be forced outwardly along the member 4 by exerting pressure upon the cross member 7.

In practice it is preferred that the penetrating member 3 comprises a steel shank although any other material can be employed which can be employed with equal facility.

I have found in practice that my improved spear is particularly adapted for use in collecting paper, trash or the like in parks, camps, yards and kindred localities.

From the foregoing description it is thought to be obvious that a spear constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and forma-

tion of the several parts herein shown in carrying out my invention in practice except as hereinafter claimed.

I claim:

- 5 1. A device of the character described comprising a handle member, a penetrating member extending outwardly from an end thereof, the adjacent end of the handle member affording a stop, a cross member 10 slidably mounted upon the penetrating member, the contact of said cross member with the adjacent end of the handle member limiting the movement of the cross member inwardly of the penetrating member, 15 and means for normally holding said cross member at the limit of its inward movement at the inner end of the penetrating member.
2. A device of the class described comprising a handle member, a penetrating member 20 extending outwardly from an end thereof, a cross member slidably mounted on the penetrating member, a second cross member slidably mounted on the handle member, means for connecting both of said cross 25 members for unitary movement, the inward movement of the cross members being limited by the contact with the first named cross

member with the adjacent end of the handle member, and means co-acting with the handle member and the second named cross 30 member for normally maintaining said members at the limit of their inward movement.

3. A device of the class described comprising a handle member, a penetrating member 35 extending outwardly from an end thereof, a cross member slidably mounted on the penetrating member, a second cross member slidably mounted on the handle member, means for connecting both of said cross 40 members for unitary movement, the inward movement of the cross members being limited by contact with the first named cross member with the adjacent end of the handle member, and retractile springs operatively engaged with the outer end portions of the second cross member and with the handle member at a point inwardly of said second cross member, said springs serving to maintain the cross members at the limit of their 45 inward movement.

In testimony whereof I hereunto affix my signature.

NICHOLS S. SCOTT.
